ATTORNEY

UNITED STATES PATENT OFFICE.

FLORENCE A. STRIETER, OF CHICAGO, ILLINOIS.

RAILROAD-GATE.

1,344,776.

Specification of Letters Patent. Patented June 29, 1920.

Continuation of application Serial No. 106,131, filed June 27, 1916. Patent No. 1,245,061, dated October 30, 1917. This application filed May 28, 1917. Serial No. 170,828.

To all whom it may concern:

Be it known that I, FLORENCE A. STRIETER, a citizen of the United States, residing at Chicago, in the county of Cook and State 5 of Illinois, have invented certain new and useful Improvements in Railroad-Gates, of which the following is a specification.

This invention relates to railway gates and particularly to that class of gates which 10 are used to obstruct the highway crossing a railroad at times when trains are approaching and crossing the highway. And this application is a continuation of application Serial No. 106,131, filed June 27, 1916, 15 which matured in Patent No. 1,245,061, granted October 30, 1917.

The object of the invention is to provide suitable mechanism for elevating, supporting and lowering the gate, when the same is 20 in use.

Of the accompanying drawings, Figure 1 is a reduced plan-view of a railroad crossing, a highway, and of a gate which I provide for obstructing the highway at the proper 25 time. Fig. 2 is a section along the line 2—2 of Fig. 1 illustrating the gate and operating mechanism which embody the features of my invention. Fig. 3 is a detail diagrammatic illustration of the electric means used. 30 Fig. 4 is an enlarged detail view of the gate supporting means. And Fig. 5 is an enlarged cross-section along the line 5—5 of Fig. 4.

In general the invention comprises a 35 chamber 8 beneath the highway 9 which is crossed by the railroad 10. The walls 11 of the chamber are made of any suitable material such as cement. Slidably mounted in the posts 12, which are inclosed and 40 vertically supported in the chamber 8, is the gate 13; the upper plate 14 of which, when the gate is down or open, rests upon the surface of the highway and closes the opening 15 in the highway through which 45 the gate is elevated. Gear racks 16 form a portion of the frame of the gate and are arranged to slide vertically in the guiding posts 12. A central rack 17, forming also a portion of the frame of the gate, may 50 be used if the gate is of sufficient length to warrant.

The operating mechanism of the gate comprises gear wheels 18 mounted on a shaft 19 journaled in brackets 20. Fixed to one end 55 of the shaft 19, is a gear wheel 21, mesh-

ing with a pinion 22, which is mounted on the shaft of the operating motor 23. The gear wheels 18 mesh with the respective racks 16 and 17 and, when the motor is operated in the proper direction, the gate will be raised to the position desired.

Suitably mounted adjacent the railroad track 10, are electric switches 26 and 27, arranged to be operated in an ordinary manner by the wheels of the train as it approaches or leaves the highway; and properly connected to these switches are electric conductors which are connected in a suitable manner to the motor 23, as is more fully described hereinafter.

In practice when the front wheels of the approaching train reach switch 26, the switch will be closed and the motor will be set in operation, rotating in the proper direction to elevate the gate; the gate will be elevated until the bottom ends of the racks pass slightly above the shaft 19; and the gate, by means hereinafter described, will be held in such position with the racks clear of the gear wheels 18, the gear wheels 20 running idle. When the front wheels of the train reach switch 27, the motor circuit will be opened, the supporting means referred to will be withdrawn, and the gate, by its own weight will be forced down to open position. Suitable weights may be used to assist in forcing the gate downward, if desired.

Fig. 3 shows diagrammatically the electric means used for operating the motor. The starting switch 26 is normally held open by means of a spring 60; and when closed, the motor is operated, and the switch is held closed by the electro-magnet 61. The switch 27 is normally held closed by the spring 62 and is arranged to be opened by the wheels of the train, thus stopping the motor. In the diagram the source of electric energy is indicated by 65, the field coils of the motor by 66, the armature coils by 67, and the connecting wires by 68.

The mechanism referred to for supporting the gate in its raised position comprises a member 24, mounted on the end of the motor shaft 23. Pivoted to the member 24 are the bell-crank levers 28 having weights 42 at their ends and playing in guide ways 43. Connecting the short ends of the levers 28, with a slidably mounted pin 44, are links 45. Slidably but non-rotatably mounted in a member 46 is a bar 47 supporting a roller 11

48. The member 46 is fixed in any suitable manner to the framework of the gate supporting means. The inner end of the bar 47 has a projection 49, which is rotatably fixed to the end of the pin 44, so that, as the pin moves longitudinally in the member 24, the bar 47 will be moved longitudinally in member 46.

In operation, as the motor rotates, the 10 weights 42 will tend to fly outwardly, and, by means of the connecting members, to push outwardly the bar 47. Normally the roller 48 is in the slot 51 of the guide bar 50 and against the edge of the rack 16 which 15 is adjacent the motor. When, however, the rack has reached the maximum elevation, the roller 48 will pass under the end of the block 53 fixed to the lower end of the rack, as indicated by the dotted lines in Fig. 4, 20 and will thus hold the rack in the elevated position.

When the train reaches the switch 27 it will be opened by the train wheels and the motor will come to rest. This will allow the 25 springs 52 to force the levers 28 inwardly, and thus to withdraw the supporting roller 48 from under the end of the rack 16. The racks will then press downwardly and

rotate backwardly the mechanism by virtue of the weight of the gate, and the gate will 30 thus pass downwardly to normal open position.

I claim as my invention:

1. The combination of a gate, means for elevating said gate, means for supporting 35 said gate when elevated, means for starting said elevating means, means for stopping said elevating means, and means operated by said elevating means for withdrawing said supporting means when said elevating 40 means stops.

2. The combination of a gate, gate elevating means, and gate supporting means, said latter means comprising centrifugal means 45 operated by said elevating means.

3. A railway gate, a member fixed to said gate, means for elevating said gate, a support for passing under said member when said gate is elevated, means operated by said elevating means for forcing said support under said member, and means for withdrawing said support when said elevating 50 means stops.

In testimony whereof I hereunto set my hand in the presence of two witnesses.

FLORENCE A. STRIETER.
